UNITED STATES PATENT OFFICE.

MILTON M. LEICHTER, OF BROOKLYN, NEW YORK.

BUCKLE-SUPPORT.

1,190,305.

Specification of Letters Patent. Patented July 11, 1916.

Application filed June 9, 1913, Serial No. 772,666. Renewed December 3, 1915. Serial No. 64,934.

To all whom it may concern:

Be it known that I, MILTON M. LEICHTER, a citizen of the United States, residing at Brooklyn, in the county of Kings and State 5 of New York, have invented certain new and useful Improvements in Buckle-Supports; and I do hereby declare the following to be a full, clear, and exact description of the invention, such as will enable others skilled 10 in the art to which it appertains to make and use the same.

This invention relates to detachable buckles and has for an object to provide an improved means for temporarily fastening 15 a buckle upon a slipper or the like.

Another object of this invention is to provide means for securing a buckle to a slipper or the like by having a tab secured to said slipper and by having said tab engage 20 a detachable buckle, after which said tab has the free end thereof secured to said slipper or the like.

Further objects will be apparent from the following specification, appended claims 25 and drawings in which,

Figure 1 is a perspective view of a pump showing the buckle supporting means fastened thereon, Fig. 2 is a perspective view showing the detachable fastening means 30 used in holding the buckle to said pump, Fig. 3 is a similar view showing a modified form, and Fig. 4 is a perspective view of the rear side of a buckle.

As it is frequently desired to have several 35 sets of buckles which may be attached to a single pair of pumps for wear on different occasions, it is necessary that some adequate provision be made to permit said buckles being applied and removed without injuring 40 the pumps as by stitching and that such provision permit quick application and removal of said buckles when desired.

I provide a means comprising a tab which may be stitched or otherwise secured to the 45 pump which tab engages a cross-piece carried by a buckle and which tab is subsequently secured to the pump so as to securely hold the cross piece of the buckle in fixed position with regard to the pump.

Referring to the drawing there is shown a pump 10 which has a tab 11 secured thereto as by stitching 12 and this tab has snap fasteners 13 secured to the under side

thereof which fasteners receive the studs 14 secured to the pump as shown.

55

The buckle 15 which may be of any appropriate form has a cross-piece 16 across the back thereof which is secured at its ends to the edges of the buckle. In applying the buckle to the pump the tongue 11 is passed 60 between the buckle and a cross-piece 16 and after said cross-piece has been moved below the fasteners 13, the free end of the tongue is secured to the pump by the fasteners 13 and 14. The tab 11 may be modified as 65 shown in Fig. 3 of the drawing in which a strip of material is bent upon itself and stitched as at 18 to form an extension 19 which may be stitched or otherwise secured to the pump as shown at 20. In this form 70 the studs 21 are secured to the flap 11 and snap fasteners 22 are secured to the extension 19 as shown.

The application and removal of a buckle to or from a pump is obvious from the foregoing and it is apparent that by permitting buckles to be temporarily secured to a pump, a single pair of pumps may be used for numerous occasions.

Various modifications may be made within 80 the scope of this invention without departing from the spirit thereof and

Having thus described my invention, I claim:

1. In combination, a slipper, a tab having 85 one end thereof permanently secured to said slipper, and coöperating securing means carried by said tab and slipper for detachably securing said tab to said slipper at a distance from said permanently secured end, 90 in order to permit a buckle having a securing bar attached thereto to be slipped over said tab to position its bar beneath the portion of the tab between said permanently secured end and the detachable securing 95 means and the subsequent securing of said tab to said slipper by means of said detachable securing means.

2. In combination, a slipper, a tab having an extension from one end thereof, means 100 for permanently securing said extension to said slipper, and coöperating securing means carried by said tab and extension for detachably securing said tab to said slipper at a distance from the end of said tab adjacent 105 said extension, in order to permit a buckle

having a securing bar attached thereto to be slipped over said tab to position its bar beneath the portion of the tab between the end thereof adjacent said extension and the 5 detachable securing means and the subsequent securing of said tab to said slipper by means of said detachable securing means.

Copies of this patent may be obtained for five cents each, by addressing the "Commissioner of Patents, Washington, D. C."

In testimony whereof I affix my signature in presence of two witnesses.

MILTON M. LEICHTER.
